UNITED STATES PATENT OFFICE.

RALPH EHRENFIELD AND NIELS HANSEN, OF WILKINSBURG, PENNSYLVANIA,
ASSIGNORS TO WESTINGHOUSE ELECTRIC & MANUFACTURING COMPANY, A
CORPORATION OF PENNSYLVANIA.

CONTROLLER.

1,390,515.

Specification of Letters Patent. Patented Sept. 13, 1921.

Application filed October 17, 1918. Serial No. 253,553.

To all whom it may concern:

Be it known that we, RALPH EHRENFIELD, a citizen of the United States, and a resident of Wilkinsburg, in the county of Allegheny and State of Pennsylvania, and NIELS HANSEN, a subject of the King of Denmark, and a resident of Wilkinsburg, in the county of Allegheny and State of Pennsylvania, have invented a new and useful Improvement in Controllers, of which the following is a specification.

Our invention relates to controllers adapted for use in connection with electric motors of small horse-power, and it has for its object to provide apparatus of the character designated which shall be neat and finished in appearance, inexpensive to manufacture, simple in construction and strong and durable in operation.

Heretofore, it has been customary to mount the controller of a sewing machine either on the treadle of the machine or independently, but the controllers built for one type of mounting could not be used for the other type of mounting.

By our invention, we provide a controller which may be mounted either on the treadle of the machine or separately and in which each part of the controller is a complete unit by itself and may, therefore, be easily replaced when necessary.

Referring to the accompanying drawings, Figure 1 is a view, partially in plan and partially in section, taken along the line I—I of Fig. 2, showing a controller constructed in accordance with our invention; Fig. 2 is a sectional view of the controller shown in Fig. 1, taken along the line II—II thereof; Fig. 3 is a sectional view taken along the line III—III of Fig. 1 and showing the movable arm in its operative position; and Fig. 4 is a sectional view along the line IV—IV of Fig. 2.

Referring more particularly to the drawing, our controller comprises a stationary member 1 and a movable member 2, both of which are mounted on a pressed steel base 3. The stationary member 1 comprises two current-limiting members 4 and 5, a plurality of contact fingers 6 which engage the current-limiting members 4 and 5 and also engage a contact-making portion 7 of the movable member 2, and a cover member 8 which is mounted on the base member 3 and

incloses the current-limiting members 4 and 5, the contact fingers 6 and the contact-making portion 7 of the movable member 2.

Each of the current-limiting members 4 and 5 comprises a coil 9 of wire of relatively high resistance and a supporting bar 10 formed of refractory insulating material. The contact fingers 6, as best shown in Fig. 4, are mounted upon a supporting base 11 composed of insulating material which, in turn, is mounted upon supports 12 that are integral with the insulating support 10. The contact-making fingers 6 are resilient and one end 13 of each of them engages the resistance wire of a current-limiting member. The other end 14 of each finger 6 engages the contact-making end 7 of the movable member 2.

The movable member 2 is pivotally mounted upon tongues 15 which are punched from the pressed-metal base 3 and bent upwardly. The contact end 7 of the movable member 2 consists of a main body portion composed of pressed metal upon each side of which is mounted a strip of insulating material 16 bearing metallic contact plates 17, connected together by metal rivets 18.

The ends 14 of the contact fingers 6 are so positioned as to engage the insulating members 16 at all times when not engaged by the conducting plates 17, during operation of the motor (not shown). By this arrangement, the contact fingers are held against the insulating members at a relatively light pressure but engage the contact members 17 at a relatively higher pressure, which is very desirable for good contact.

Also, by this arrangement, a very good contact is made with a minimum movement of the contact fingers, and the possibility of the contact arm being engaged by the ends 14 of the contact fingers, thus preventing its operation, is precluded. It will, of course, be understood that the contact members 17 may be mounted in recesses in the insulating material 16 so that the metallic surface 100 and the insulating surface are flush, the pressure of the contact fingers causing a good contact to be established therewith.

The contact fingers 6 are all of substantially the same length and shape, and the contact plates 17 are so positioned upon the insulating members 16 as to make successive engagement with the contact fingers when

the member 2 is actuated. By this arrangement, the assembly and the manufacturing cost of the contact fingers 6 are greatly reduced.

- 5 The cover member 8 is provided with a flange 19 which engages flanges 20 punched from the pressed-metal base member 3 on each side thereof. The cover member 8, being of pressed metal, is easily sprung to 10 cause the flanges 19 to extend beneath the tongues 20, thus providing a firm and rigid connection and causing the controller to present a neat and finished appearance.

When the controller is independently 15 mounted, the movable member 2 is operated by exerting pressure upon a foot pedal 21, thus causing the contact plates 17 to engage the contact fingers 6 in succession. When it is desired to mount the controller upon 20 the treadle of a sewing machine, the member 3 is attached thereto by means of bolts, not shown, extending through openings 22 therein, and a chain (not shown) extends from the table portion of the sewing machine 25 (not shown) to an opening 23 in the contact-making end 7 of the movable member 2, so that pressure exerted upon the treadle member of the sewing machine will cause the contact plates 17 to engage the contact fingers 6 in the manner previously described.

Throughout this specification and the claims, the word "independent" should be defined as "free from the treadle."

While we have shown but one form of our 35 invention, it will be obvious to those skilled in the art that it is not so limited but is susceptible of various minor changes and modifications without departing from the spirit thereof, and we desire, therefore, that only 40 such limitations shall be placed thereupon as are imposed by the prior art or are specifically set forth in the appended claims.

We claim as our invention:

1. In a controller, a movable member comprising a pivoted lever provided with an insulating surface, a plurality of resilient contact fingers adapted to normally engage said insulating surface at a relatively light pressure, and a plate of conducting material 50 mounted on said insulating surface to engage said contact fingers at a relatively heavy pressure upon movement of said lever.

2. A controller comprising a resistor consisting of a resistance wire wound upon an insulating support, a plurality of contact fingers mounted upon a separate insulating base and adapted to engage said resistance wire, and a movable contact member disposed to engage the other ends of said contact fingers. 55

3. A controller comprising a plurality of contact fingers of substantially equal length mounted upon a flat surface in a substantially straight line, and a movable member adapted to engage said contact fingers and 60 pivotally mounted near one end of said line of contact fingers, said movable member being disposed at an angle to said flat surface when engaging said contact fingers.

4. In a controller, a plurality of resilient 70 stationary contact members, a movable member comprising a pivoted arm, a plate composed of insulating material mounted on each side of said arm and normally in engagement with said contact members, and a 75 conducting plate mounted on each of said insulating plates and adapted to engage said contact members upon actuation of the movable arm.

5. A controller comprising two spaced 80 side-by-side resistors, a plate composed of insulating material mounted adjacent said resistors, two spaced rows of resilient contact members mounted on said plate and having one end in engagement with one of 85 said resistors and having the other end free, the free ends of the two rows of contact members being spaced apart, and a movable contact member adapted to move between and to engage said rows of free ends. 90

6. In a controller, a movable element comprising an arm pivoted intermediate its ends and means for normally retaining said arm in a predetermined position, one end of said arm being adapted to receive pressure to actuate the same and the other end of said arm being adapted to receive a pull or tension to 95 actuate said arm.

In testimony whereof, we have hereunto subscribed our names this 30th day of Sept., 100 1918.

RALPH EHRENFELD.
NIELS HANSEN.
